UNITED STATES PATENT OFFICE.

WELLINGTON RANDALL, OF MARYSVILLE, WASHINGTON.

CAR-AXLE.

1,109,464.

Specification of Letters Patent.

Patented Sept. 1, 1914.

Application filed May 16, 1914. Serial No. 839,038.

To all whom it may concern:

Be it known that I, WELLINGTON RANDALL, a citizen of the United States, residing at Marysville, in the county of Snohomish and State of Washington, have invented certain new and useful Improvements in Car-Axes, of which the following is a specification.

My invention relates to improvements in car axles of the divided type and resides in the provision of an inexpensive and durable car axle that will enable independent turning of the wheels so as to eliminate wear on the wheels and strain on the axle in rounding a curve.

An object of importance is to provide novel means for securely holding the divided axle in assembled position in such a way that the wheels are permitted to turn relative to each other and the axle will rotate freely.

Another object of importance is to provide lubricating means arranged in a novel manner so that the axle is lubricated in a most reliable manner thus eliminating unnecessary wear on the bearings.

Another object of importance is to provide an axle of the character described that is simple as to construction, reliable and efficient in operation and inexpensive to manufacture.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts, Figure 1 is a longitudinal sectional view taken through my improved divided axle showing the same as it would appear when in assembled position, Fig. 2 is a transverse sectional view taken on the plane of line 2-2 of Fig. 1, Fig. 3 is a transverse sectional view taken on the plane of line 3-3 of Fig. 1, and Fig. 4 is a fragmentary detail perspective view of one of the parts of the divided axle and bearing members thereon.

Referring to the drawings by characters of reference the numeral 1 designates as an entirety, a divided axle consisting of two semi-cylindrical rods or axle portions 2 that are secured to each other to provide a cylindrical axle and have shrunk on their ends as at 3 the usual flanged railway wheels 4.

As a means for securely holding the axle portions 2 in assembled position, I provide coöperating semi-cylindrical members 5 that are equal in length approximately to the distance between the inner faces of the wheels, are similar as to construction and provided upon their flat faces with grooves extending longitudinally to coöperate and receive the axle 1.

To clamp the members 5 I provide bands or rings 6 at the ends of the members 5 which surround said ends and are preferably shrunk on. The members 5 are of larger diameter at the center than at the ends, being made tapering from the center to the ends as shown in Fig. 1 in the drawings. A ring 7 of larger diameter than the ones 6 is mounted upon the central portion of each of the members 5 so as to surround the same and is shrunk on in the same manner as are the rings 6.

The axle 1 comprises four axle portions 2, each being semi-cylindrical in cross section. The axle 1 is divided at the center. Thus each of the axle members 2 is equivalent to half the length of the axle as a whole. On each of the axle portions 2 is placed a semi-cylindrical bearing flange 8 that when fitted to the flanges comprises a cylindrical bearing portion. It will thus be seen that a bearing portion is provided for each half of the axle and said bearing portions are arranged to engage each other at their inner faces as shown in Fig. 1 in the drawings. The lower member 5 is provided with a semi-circular recess 9 centrally of its ends and in its flat face, arranged transversely of the member and snugly receives the bearing portions comprising the members 8. Mounted between the portions 8 is a circular wear plate 9' that fits snugly within the recess 9 and prevents unnecessary wear on the bearing portions 8. Formed in the opposing face

- of the recess 9 is a larger recess 10 formed larger to provide a lubricant receiving compartment. The members 8 are arranged centrally of the sides of the recess 10.
- 5 The band or ring 7 is provided upon its upper face with a recess 11 in which is mounted an oil cup 12. The inner end of the oil cup communicates with divergent oil passages 13 that communicate with the 10 recess 10 on opposite sides of the bearing members 8. The outer face of the oil cup 12 is disposed approximately flush with the outer surface of the upper member 5. Semi-circular recesses 14 similar to the one 15 10 are formed in the opposed faces of the members 5 adjacent to the ends thereof and receive semi-cylindrical bearing portions 15 rigidly connected with the axle members 2. The inner faces of the bearing portions 15 20 engage certain side faces of the recesses 14. The bearing members 15 are similar to the ones 8 and are arranged so that the recesses 10 provide oil receiving compartments. The bands or rings 6 are recessed on their 25 outer and upper faces as at 16 to receive oil cups 17 that have their outer faces flush with the bands 6 and inner ends communicating with the recesses 14. Arranged intermediate the end members 15 and central 30 members 8 are bearing members 18 similar to the ones 8 and 15 and mounted in recesses similar to the ones 9 and 10. A passage 19 is formed on opposite sides of the opposite sides of the recess 10 and communicates at 35 its ends with the recesses for the members 18 in the upper member 5 and the recess 10. This arrangement provides for the lubrication of the members 18.
- It will be readily seen that I have provided novel lubricating means for my improved divided axle that will serve in an extremely effective manner to expeditiously lubricate all of the bearing parts of my device so as to prevent undue friction and 45 wear. The rings 6 and 7 not only serve to secure the parts 5 together but serve to hold oil cups in such a way that they do not interfere with the attaching of the axle to railway cars.
- 50 It will be readily seen that with my improved device the wheels 4 are permitted to move relative to each other and thus a great amount of wear is eliminated in rounding curves and under other conditions.
- 55 In practice, I have found that the form of my invention, illustrated in the drawings and referred to in the above description, as the preferred embodiment, is the most efficient and practical; yet realizing that the 60 conditions concurrent with the adoption of my device will necessarily vary, I desire to emphasize the fact that various minor changes in details of construction, propor-

tion and arrangement of parts may be resorted to, when required, without sacrificing any of the advantages of my invention, as set forth.

What is claimed is:—

1. A car axle comprising a plurality of semi-cylindrical portions secured to each other to provide a divided axle, car wheels secured to the outer ends of the divided parts of the axle, semi-cylindrical bearing members secured to the inner ends of each divided part of the axle, a pair of semi-cylindrical members having longitudinally grooved flat faces to clamp the divided portions in position, rings securing the semi-cylindrical portions to each other, and means to lubricate the bearing members. 75
2. A car axle comprising a plurality of semi-cylindrical portions secured to each other in pairs to provide a divided axle, the divided portions of the axle being of equal length, car wheels rigidly secured to the outer ends of the divided parts of the axle, bearing members arranged at the ends and intermediate the ends of the divided parts of the axle, coacting semi-cylindrical members arranged to clamp the semi-cylindrical portions comprising the axle to each other and having recesses to receive the bearing members, means to secure the coacting members to each other and lubricating means for the bearing members. 80
3. A car axle comprising a plurality of semi-cylindrical portions secured to each other in pairs to provide a divided axle, the divided portions of the axle being of equal length, car wheels rigidly secured to the outer ends of the divided parts of the axle, bearing members arranged at the ends and intermediate the ends of the divided parts of the axle, coacting semi-cylindrical members arranged to clamp the semi-cylindrical portions comprising the axle to each other and having recesses to receive the bearing members, and means to secure the coacting members to each other. 85
- 95
4. A car axle comprising a plurality of semi-cylindrical portions secured to each other in pairs to provide a divided axle, car wheels rigidly secured to the outer ends of the divided portions of the axle, bearing members secured to the ends and intermediate the ends of the divided parts of the axle, semi-cylindrical members provided with longitudinally grooved flat faces to clamp the semi-cylindrical portions of the axle into engagement with each other, said last named semi-cylindrical portions being of greater diameter in the center than at the ends and tapered from the center to the ends, rings mounted upon the ends of the semi-cylindrical members and a ring arranged centrally of the ends of the semi- 100

cylindrical members, said semi-cylindrical members being recessed transversely to receive the bearing members, certain of said recesses being larger than the others to provide oil receiving compartments, and lubricating means communicating with said compartments.

In testimony whereof I affix my signature in presence of two witnesses.

WELLINGTON RANDALL.
